UNITED STATES PATENT OFFICE.

EDWARD O. BENNETT, OF LOS ANGELES, CALIFORNIA.

INTERNAL-COMBUSTION ENGINE.

Application filed September 30, 1926. Serial No. 138,711.

The present invention is an improved internal combustion engine. The objects of my invention include:

- (1) the provision of an engine of the character described which will economize in weight as well as in fuel consumption, and will effect a conservation of space, and afford easy accessibility of parts for removal, replacement or adjustment.
- 10 The present invention contemplates a two cycle engine and this type is shown in the drawings, but many of the advantageous features hereinafter described are serviceable in and applicable to the 4 cycle type.
- 15 Another object of the invention is a structure dispensing with intake and exhaust valves (in the commonly accepted sense), and the elimination of many parts usually regarded as essential to engines.
- 20 Another object of this invention, which is of distinctive advantage, is the provision of a structure which is grouped closely around the driven shaft, occupying relatively small space and composed of few parts, which are easily removable rendering the engine adaptable to marine duty. In such installations my engine can be directly connected to the propeller shaft without the necessity of offsetting same or altering the 25 pitch. This feature and the elimination of a reverse gear effects a very economical installation in marine motors.
- Again, the structure hereinafter described is particularly applicable to airplane duty, being light, powerful and rugged, and easily installed on a propeller shaft in tandem relation, if desired. Because of its peculiar structure it is not liable to many of the 30 faults common to airplane engines. No timing gears are employed, no cam shafts or 35 gearing and all the parts are direct acting.

Other objects and advantages will appear as this description proceeds.

In this specification and the annexed drawings, the invention is illustrated in the form considered to be the best, but it is not limited to such form because it may be embodied in other forms, and it is also to be understood that in and by the claims following the description it is desired to cover the invention in whatever form it may be embodied.

In the accompanying two sheets of drawings

Figure 1 is a longitudinal view of my en-

gine in twin form a portion of said view being shown in vertical longitudinal cross section and a portion thereof in side elevation,

60

Figure 2 is a top plan view partly in section of a bed plate casting showing bearings which sustain the working parts of my engine,

Figure 3 is a central transverse section of 65 Figure 2, taken on the lines III—III;

Figure 4 is a cross section of a spool shaped member on the irregular line IV—IV of Figure 1,

Figure 5 is a side elevation of a piston 70 ton,

Figures 6 and 7 are sections of Figure 5 taken on the line VI—VI and VII—VII,

Figures 8 and 9 are respectively top and bottom plan views of the piston shown in 75 Figure 5,

Figure 10 is an outside elevation of a cylinder showing the exhaust side,

Figures 11 and 12 are cross sections of Figure 10 taken on the lines XI—XI and 80 XII—XII,

Figures 13 and 14 are respectively end elevation and side elevation of a split collar cam.

Referring to the drawings the numeral 1 85 indicates in its entirety, a crank case casting in substantially rectangular form, provided with lugs 2, at the corners and intermediate the length thereof, having bolt openings 3 for securing the crank case to a suitable foundation (not shown). Cast integral with crank case 2 are bearings, indicated in Figure 2, 4 and 6, indicating the end bearings, and 7 and 8 indicating twin center bearings.

Bearing standards 8' are secured to the bearings 4 and 6 by bolts extending through the openings 3. The upper end of the standards 8' form a split bearing, said bearings being the outside bearings which support trunnions 11^a and 11^b on cylinders 12^a and 12^b oscillatively mounted in said bearings. The trunnions on the side remote from the standards 8' have their bearing in the ends of a casting 13, Figure 1, and said casting 13 is provided with twin bearings in the base which register with and are secured to the twin bearings 7 and 8 in the crank case 1, being secured thereto by bolts passing through openings 14 in said crankcase.

In my engine I employ a composite crank shaft flywheel and compressor mechanism,

95

100

105

110

and, for the purposes of simplicity in description, I will now describe the external assembly which forms the crank shaft and flywheel and, later, describe the internal mechanism and coacting parts which admit, compress, and distribute air and fuel.

At 16 I show a disc circular in form having integral crank 17, the offset portion 16^a of which is supported in the split bearing 4 of the crank case 1 and standard 8'. The disc 16 is secured as by bolts 15 to a spool-shaped member 18. As the spool-shaped member 18 is symmetrical, having similar functions on each of its ends, and as the crank shafts 16^a and discs 16 joined to said spool are identical, and secured to said spool in the same manner, but one will be described, and in Figure 1, this assembly is shown partly in section and partly in elevation for the purposes of better illustration. The cranks 17 are in eccentric relation to the discs 16 and in assembly said cranks 17 are diametrically opposed when the parts are bolted together by bolts 15. When so assembled a crank shaft is formed, the ends 16^a of which are supported in the end bearings 4 and 6 of the bed plate, and the spool member 18 has its bearing in a bushing 19, Figures 13 and 14, which in turn rests in the twin bearings 7 and 8 at the center of the bed plate (said bushing being mounted for limited rotation in said bearings for purposes to be later described). When so assembled the parts form a crank shaft, the spool member 18 and the discs 16 serving as a flywheel, while the cranks 17 are engaged by split bearings 21 in the end of a piston 22, Figure 5. The piston 22 reciprocates in a cylinder 12^b. Each reciprocation of the piston 22 rotates the crank 16 one revolution, and the cylinder 12^a rocks on its trunnions 11^a.

I will now describe means contained within and associated with, the spool member 18 of the composite flywheel and crank shaft for admitting, compressing, and distributing air and fuel. At 23 I show a rod connecting a pair of pistons 24^a and 24^b in dumb-bell relation, said rod 23 being slideable longitudinally in a bore 20 extending through the spool member 18. The pistons 24^a and 24^b are provided with the conventional split packing rings 26. The pistons 24 fit snugly in chambers 27^a in the enlarged portions of the spool member 18. In order to cause the reciprocation of the dumb-bell piston structure to admit and distribute compressed air I provide the following mechanism. The rod 23 is provided with a rack section indicated at 28, Figure 1, for engagement with a toothed segment 29 pivoted on a bolt 31. The bolt 31 extends through bearings 32, Figure 4, integral with the spool 18. At 33 I show a reinforcing web of metal giving rigidity to the bearings 32 and said

web rotates with said spool through a cam slot, indicated at 34, Figures 1 and 14. The purpose of the oblique cam slot 34 is to guide and actuate (during the rotation of said spool) a roller 36 secured to and revolute on the segment 29, and thereby reciprocate the dumb-bell pistons 24^a and 24^b (through the rack and tooth engagement of segment 29 with the rod of said piston), the segment 29 serving as a lever fulcrumed on pin 31, force being applied by the stationary cam slot 34 to the roller 36. It results from this structure so far described that one revolution of the crank shaft (or spool 18) will effect one reciprocation of the dumb-bell pistons 24^a and 24^b and compress fluid in the chambers 27^a and 27^b. Each of said chambers has a function on either side of pistons 24^a and 24^b, said chambers being divided by the pistons 24^a and 24^b, one side 27^b of a piston compressing a fuel charge and the opposite side 27^a of said piston (on the return stroke) compressing air for scavenging the products of combustion from the cylinder in a manner to be later described.

Referring to Figure 1, assuming that the engine is rotated in a clockwise direction to a spectator standing on the left of said figure the dumb-bell piston 24^a will move to the right compressing fuel in chamber 27^b which passes through passages 37 in the crank 17 which open on the periphery of said crank and discharge into a chamber 38 of piston 22 slideable in a cylinder 12^a. Passages 42 are bored obliquely in the head of said piston terminating on the periphery thereof in register with slots 43 in the inner wall of the cylinder 12^a. When the piston 22 moves up into cylinder 12^a till the ports 42 register with the slots 43 the compressed fuel enters the cylinder 12^a. The piston in its upward movement passes the upper ends of the slots 43 thus cutting off the fuel supply and the continued movement of said piston gives the fuel charge its final compression until it is fired by the spark plug 44. On the return stroke of piston 22 exhaust ports 46 are uncovered, allowing the products of combustion to escape through exhaust ports 46, communicating with a passage 47 leading to the hollow trunnion 11^a. As the piston 22 descends the piston 24 returns, the opposite face 27^a of said piston compressing air in chamber 27^a. The air compressed in chamber 27^a passes through a port 48 which at this time is in register with a passage 49 in the bushing 19, said passage leading to a chamber 51, which opens into a compressed air chamber 52 in the casting 13. A passage of air from chamber 51 to chamber 52 is governed by check valves 53, the stems of which are slideable in bosses in said casting 13. The valves 53 are normally urged to their seats by the springs 54. The upper stems are

guided in a bar 56 which rests upon lugs 57 in the chamber 52, being secured thereto by screws 58. The air compressed in chamber 27^b accumulates in chamber 52 until released 5 by the registration of a port 59 in the wall of the cylinder 12^b with a similar port 60 in a cup 65. (Port 59 occurs in the cut-away portion of cylinder 12^b.) When that port 59 in cylinder 12^b comes into register with 10 opening 60 in the end of a cup member 65 compressed air in the chamber 52 rushes through the cylinder 12^b expelling the products of combustion through exhaust ports 46, through a passage 47, and out through 15 trunnion 11^b to any suitable exhaust manifold (not shown). It will be understood that the registration of the port 59 occurs as the cylinder 12^b rocks on its trunnions. There being no wrist pin or connecting rod 20 in this type of engine, the crank movement is compensated by the oscillation of the cylinders which are pivoted on trunnions.

In order to clarify the description, the explanation of the compression of fuel 25 charge and air for scavenging, I wish to state that the entire mechanism is similar on opposite sides of the central line, indicated in Figure 1, at C—C, the parts being, of course, in right and left relation and the 30 piston heads 24^a and 24^b perform exactly the same functions.

When the dumb-bell piston is moved in one direction it serves cylinder 12^a with a fuel charge, and cylinder 12^b with a 35 scavenging charge, and, when said dumb-bell piston is actuated in the opposite direction, it serves 12^b with a fuel charge and 12^a with a scavenging charge.

While the outside surface of a piston is 40 forcing a fuel charge to cylinder 12^a the corresponding face of the twin piston is drawing in a fuel charge to be later delivered to cylinder 12^b.

I will now describe the means by which 45 air and fuel is admitted to the chambers 27^a and 27^b. The operation will be more easily understood if it is kept in mind that the adjacent chambers 27^a at all times compress and distribute air, while the chambers 50 27^b at the remote ends of the dumb-bell piston at all times compress and distribute a fuel charge.

Referring to Figures 2 and 3 I show a 55 compartment 63 in the base of the crank case casting 1, to which air is admitted through a pipe 64 threaded in the wall thereof. The split bearing portion of the crank case is provided with slots 66 which register with ports 67 in the cam bushing 60 19, Figures 1, 13 and 14, as the same rotates in the bearing of the crank case.

In the crank case casting 1, I show compartments 68, similar to the compartment 63 being separated therefrom by a parting wall 69. 65 These compartments 68 contain fuel ad-

mitted through pipes 71 from any suitable source, such as a carburetor (not shown).

I have purposely avoided showing carburation, ignition and lubrication means as any of several well known types are applicable to my engine. It will be understood that lubricating medium might be mixed with the fuel or might be injected with the scavenging charge already described. 75

Obviously, my engine may be timed and reversed by a slight rotation of the cam bushing member 19, Figure 14. This will alter the position of the cam slot 34 and advance or retard the dumb-bell piston so movement in a degree corresponding to that of said movement.

Referring to Figure 1 the cup members 65 are urged to seat in the ends of the hollow trunnions of the cylinders 12^a and 12^b by a 85 coiled spring 72 which extends into said cups. The urge of the spring 72 keeps the cups firmly seated and thus compensates for wear due to oscillation of the cylinders. The timing of the admission of the scaveng- 90 95 65 affording a means of rotating said cups simultaneously.

Fuel entering compartment 68 through pipe 71 passes in through slots 75, Figure 2, through ports 77 in bushing 19, thence 100 through a groove 78, Figures 1 and 4, in the spool member 18, through a passage 79 in the rod 23 of the dumb-bell piston thus entering chamber 24^b.

Air entering compartment 63 through 105 pipe 64 passes through slots 66, through ports 67 in bushing 19, thence through a groove 81, Figures 1 and 4, in spool 18, and passes to chamber 27^a through a groove 82 in the periphery of rod 23. 110

I claim:

1. In an engine, the combination with a base member and a pair of cylinders oscillatively mounted thereon, of a composite flywheel and crankshaft, pistons reciprocable in said cylinders and directly connected to said crankshaft, said pistons and said crankshaft provided with passages communicating, when in register with the combustion chambers of said cylinders, and means in said composite crankshaft and flywheel, responsive to the rotation thereof, for alternately scavenging one of said cylinders and refueling the other through said passages. 115

2. In an engine a composite crankshaft and flywheel comprising a shaft provided with a crank and with an enlarged hollow flywheel portion concentric with said shaft, a piston reciprocable in said flywheel portion adapted, when reciprocated, to alter- 120 125 130

nately intake and discharge air and fuel through passages extending through said composite shaft.

3. In an engine a composite crankshaft and flywheel comprising a shaft provided with a crank and with an enlarged hollow flywheel portion concentric with said shaft, a piston reciprocable in said flywheel portion adapted, when reciprocated, to alternately intake and discharge air and fuel through passages extending through said composite shaft, and means cooperating with a stationary part, for causing rotation of said crank shaft to reciprocate said piston.

4. An internal combustion engine comprising a base member, a pair of cylinders oscillatively mounted on said base, pistons reciprocable in said cylinders, a composite crankshaft and flywheel, the cranks of which are directly connected to said pistons, said crankshaft and said pistons provided with passages therethrough which, when in register, communicate with the combustion chambers of said cylinders, and said crankshaft also provided with enlarged hollow flywheel portions concentric with said shaft, a dumb-bell piston adapted to reciprocate in said hollow portions when said shaft is rotated, and, by its reciprocation, to alternately scavenge one of said cylinders and refuel the other through said communicating passages in said piston and said crankshaft.

5. In a two cylinder engine a composite crank shaft and flywheel comprising a shaft

provided with crank portions, pistons reciprocable in said cylinders and directly connected to said crank portions, said shaft also provided with hollow enlarged portions, concentric with said shaft, a dumb-bell piston, reciprocable in said hollow portions and adapted, when reciprocated, to simultaneously serve both of said cylinders by alternately scavenging one of said cylinders and simultaneously refueling the other through passages extending through said composite shaft and communicating during a portion of each rotation with passages through said pistons.

6. In a two cylinder engine a composite crankshaft and flywheel comprising a shaft provided with crank portions, pistons reciprocable in said cylinders and directly connected to said crank portions, said shaft also provided with hollow enlarged portions concentric with said shaft, a dumb-bell piston, reciprocable in said hollow portions and adapted, when reciprocated, to simultaneously serve both of said cylinders by alternately scavenging one of said cylinders and simultaneously refueling the other through passages extending through said composite shaft and communicating during a portion of each rotation with passages through said pistons, and means, responsive to the rotation of said shaft, for reciprocating said dumb-bell piston.

In testimony whereof I affix my signature.
EDWARD O. BENNETT.
